Atty.

UNITED STATES PATENT OFFICE.

JOHN STRAKA, OF CHICAGO, ILLINOIS, ASSIGNOR OF ONE-HALF TO JOSEPH R. LEWIS,
OF CHICAGO, ILLINOIS.

MAGAZINE PENCIL.

1,421,712.

Specification of Letters Patent. Patented July 4, 1922.

Application filed October 16, 1920. Serial No. 417,432.

To all whom it may concern:

Be it known that I, JOHN STRAKA, a citizen of the present Government of Czechoslovakia, and a resident of Chicago, Cook County, and State of Illinois, have invented certain new and useful Improvements in Magazine Pencils, of which the following is declared to be a full, clear, and exact description.

- 10 This invention relates to pencils and among its objects are to provide simple automatic and improved mechanism for feeding out the lead when the point thereof has become worn down, or in case of breakage.
- 15 Another object is to provide reciprocating or endwise movable lead feeding mechanism in a pencil. Another object is to provide lead feeding mechanism arranged to feed out a measured or given amount of lead
- 20 each time the lead feeding mechanism is actuated. Other objects and advantages will appear in the course of the following specification and with all of said objects and advantages in view, this invention consists
- 25 in the several novel features of construction, arrangement and combination of parts as will hereinafter more fully appear.

The invention is clearly illustrated in the accompanying drawing, in which;

- 30 Fig. 1 is a side elevation of a pencil, embodying a simple form of the present invention; Fig. 2 is a central, longitudinal section thereof; Fig. 3 is a detail cross section taken on line 3—3 of Fig. 2; Fig. 4 is a detail cross section taken on line 4—4 of Fig. 2; Fig. 5 is a detail cross section taken on line 5—5 of Fig. 2; Fig. 6 is a detail cross section taken on line 6—6 of Fig. 2; Fig. 7 is a side elevation of a certain
- 35 member of the lead feeding mechanism; Fig. 8 is a detail cross section taken on line 8—8 of Fig. 7; Fig. 9 is a detail cross section taken on line 9—9 of Fig. 7; Fig. 10 is a perspective view of a certain lead feeding plunger and Fig. 11 is a side elevation of a certain lead feeding tube. Figs. 2 to 11, inclusive, are upon a greatly enlarged scale.

Referring to said drawing, which illustrates a simple embodiment of the invention, the reference character 12 designates the casing or outer shell of the pencil, having a tapering end 13 beyond which is the tip 14 from which projects the point or end 55 of the lead 15. The casing may be of cylind-

rical or hexagon form, as is found desirable.

In said casing or shell 12 is fixedly secured a tube 16, which is axially disposed with respect to the casing and extends from the end of the tapered part 13 to a suitable place in the casing, depending on the length of leads to be used, and upon the form of magazine employed. In the form shown the tube 16 extends throughout the greater length of the casing and is secured therein by centrally apertured walls 17, 18, that conform to the inner face of the casing and are held therein by friction. If desired, the end 19 of the tube 16 may be closed as shown, although this is not material.

Slidably and rotatively mounted in said fixed tube 16 is a guide tube 20, which projects into the tip 14 and is fixedly secured thereto. The end 21 of the tube 20 is preferably reduced in diameter and its wall is made thinner than the remainder of the tube and is split, as at 22, and the split portions are bent slightly toward each other to provide a slight grip upon the lead 15 for the purpose of preventing the lead from accidentally dropping out of the tube 20.

In said guide tube 20 is a plunger 23 which has a round or cylindrical part 24 that fits in the bore of the tube, and its end 85 engages the adjacent end of the lead 15. One end of the plunger is flattened, as at 25, and bent laterally of the part 24 so as to extend at an angle thereto. Said bent end portion 25 projects out through a lengthwise extending slot 26 which is formed in the guide tube 20, and engages with teeth, tongues or ratchet like elements 27 that are formed or provided upon the fixed tube 16. The normal inclination of said flat part 25 90 is greater than that shown in Fig. 2, so that the tooth or ratchet element with which the plunger is in engagement, acts to depress the flat part 25, thereby causing the plunger to bind perceptibly in the guide tube at the places lettered *a*, *b*. The purpose of this is to provide sufficient friction between the plunger and tube to prevent the plunger from being jarred or accidentally disconnected from the teeth 27. Said 105 teeth may be formed by slotting the tube 16 transversely as at 28, to leave the teeth or tongues 27 between the slots, and the ends of the slots 28 are tapered as at 29, the purpose of which will appear later. Conveniently

the tube 16 may be made of a strip of flat stock, having the slots formed therein, and it is rolled up into tubular form. At the slotted part it is preferred to have the 5 tongues or teeth 27 made flat and to have them extend in a plane substantially tangential to the cylindrical wall of the tube 16. (See Fig. 9.) It will be observed that the extreme end of the flat part 25 of the 10 plunger is arranged to engage with edge portions of the teeth. The plunger and lead are thereby positively held from being pushed back by pressure on the point of the lead.

15 To load the pencil, the guide tube is withdrawn and a length of lead inserted into the guide tube through the tip. The flat end 25 of the plunger is then pressed back and the guide tube inserted into the fixed 20 tube of the casing, with the flat bent part of the plunger being made to enter on the side opposite the teeth or tongues. When fully inserted, the tip is turned in the proper direction to bring the flat bent end of the 25 plunger into one of the notches between the tongues, and by turning said tip the proper direction, said flat bent part in moving from the round part of the tube onto the flat tongue or into a notch will snap thereinto 30 and notify the user that it is in place. To move the plunger end out of the notch, the tip is turned in the same direction thereby causing the plunger end to ride up the inclined end of the slot.

35 To feed a small portion of the lead out through the tip, the tip is pulled outward far enough to bring the terminal end of the flat part 25 of the plunger into the adjacent notch 29. On account of the friction between the plunger and guide tube, the plunger moves with said tube and tip when the tip and tube are moved outward, and the lead consequently is moved outward in front of the plunger. The tip is then pushed back 40

45 against the tapered end of the casing and the tube 20 is therewith pushed back, but the plunger is held against backward movement by reason of its engagement with the tooth or tongue of the fixed tube 16. By pushing back the tip, it exposes the point or end that was advanced when the tip was pulled outwardly and if the plunger was accidentally moved past two or more teeth, the tip need not be moved back against the tapered 50 end of the casing, but it may be moved only part way, so that only a slight part of the lead may be exposed, to guard against breaking it, it being understood that leads of very small diameter may be used in connection 55 with this pencil.

60 A supply of leads may be kept in the pencil for future use, and a magazine 30 is provided around the fixed tube to receive such leads, or the magazine may be contained in 65 the casing beyond the lead feeding mecha-

nism. As shown, the wall 18 is formed with arcuate slot 31 through which lead may be inserted into the magazine 30. The shell 12, tube 16, and walls 17, 18, form an annular like magazine that holds a large supply of leads. A cover is provided to close the end of the casing and prevent the escape of the leads, and said cover is constructed and arranged to hold a novel eraser support 70 which will now be described.

75 Slidably and removably secured in the open end of the casing 12 is a sleeve 32, in which is fixedly secured a nut or threaded washer 33, in which is mounted a threaded stem 34, that is fixedly secured to a disc 35, 80 which is formed with barbs or sharp prongs that engage with the rubber eraser 36. A cap or cover 37 is slidably and removably secured on the protruding part of the sleeve 32 and incloses the eraser. When the eraser is worn down it is given a few turns in the sleeve and the threaded pin 34 thereby moved outward by reason of its threaded connection with the nut 33. The end of the eraser is thereby moved out through the sleeve 32 to 85 expose more of its body.

90 A clip 38 is provided for securing the pencil in the pocket of one's clothing and said clip has a shank 39 which extends in through a hole in the casing and is frictionally held in place between the inner face of the casing and a sleeve 40, which is frictionally held in the casing. Said sleeve 40 may be formed integral with the end wall 18, if desired.

95 More or less variation of the exact details of construction is possible without departing from the spirit of this invention; I desire, therefore, not to limit myself to the exact form of the construction shown and described, but intend, in the following claims, to point out all of the invention disclosed herein.

100 I claim as new, and desire to secure by Letters Patent:

110 1. A pencil comprising a casing, a stationary tube therein provided with a row of plunger engaging elements, a reciprocatory tube slidably mounted in said stationary tube, a pencil tip fixedly secured to 115 said reciprocatory tube, beyond the casing, whereby said reciprocatory tube may be actuated, and a lead feeding plunger frictionally held in said reciprocatory tube and arranged to engage the plunger engaging 120 elements of the stationary tube.

125 2. A pencil comprising a casing, a stationary tube therein having a row of teeth formed therein, a reciprocatory plunger actuating tube slidably mounted in said stationary tube, a pencil tip fixedly secured to said reciprocatory tube, beyond the casing, whereby said reciprocatory tube may be actuated, and a lead feeding plunger movable lengthwise in said reciprocatory tube 130

and having a laterally bent part engaging with the teeth of said stationary tube.

3. A pencil comprising a casing, a stationary, transversely slotted tube centrally disposed therein, a reciprocatory plunger actuating tube slidably mounted in said stationary tube, a pencil tip fixedly secured to said reciprocatory tube, beyond the casing, whereby said reciprocatory tube may be

10 actuated, and a lead feeding plunger movable lengthwise in said reciprocatory tube, and arranged to engage in the slots of said slotted tube.

4. A pencil comprising a casing, a stationary tube therein having a row of teeth formed therein, a lengthwise slotted reciprocatory plunger actuating tube slidably mounted in said stationary tube, a pencil tip fixedly secured to said reciprocatory 20 tube, beyond the casing, whereby said reciprocatory tube may be actuated, and a lead feeding plunger slidably mounted in said reciprocatory tube and having a laterally extending depressible part projecting 25 through the slot of said reciprocatory tube and arranged to engage the teeth of said stationary tube.

5. A pencil comprising a casing, a stationary transversely slotted tube therein, a lengthwise slotted reciprocatory plunger actuating tube slidably mounted in said sta-

tionary tube, a pencil tip fixedly secured to said reciprocatory tube, beyond the casing, whereby said reciprocatory tube may be actuated, and a lead feeding plunger slidably mounted in said reciprocatory tube and having a laterally extending depressible part projecting through the slot of said reciprocatory tube and arranged to engage in the slots of said stationary tube. 35

6. A pencil comprising a casing, a stationary, transversely slotted tube therein, the ends of the slots being closed and one of the ends of the slots being inclined, a lengthwise slotted reciprocatory plunger actuating tube slidably mounted in said stationary tube, and a lead feeding plunger slidably mounted in said reciprocatory tube and having a laterally extending depressible part projecting through the slot of said reciprocatory tube and arranged to engage in the slots of said stationary tube. 40

7. In a pencil, a fixed tube formed with transverse, closed slots and flat tongues therebetween adapted for engagement with a depressible lead feeding plunger. 55

8. In a pencil, a fixed tube, slotted transversely to form plunger engaging tongues, said tongues being flat and overlapping the adjacent edge of the tube, and the opposite ends of the slots being inclined. 60

JOHN STRAKA.
